GUSTAVE F. BAHR, OF FAIRFIELD, CONNECTICUT, ASSIGNOR TO COLUMBIA PHONOGRAPH COMPANY, INC., OF BRIDGEPORT, CONNECTICUT, A CORPORATION OF CONNECTICUT

WINDING MECHANISM

Application filed April 12, 1930. Serial No. 443,692.

This invention relates to phonographs or talking machines and has particular relation to the means for winding the spring motors of such machines.

In certain types of these machines particularly in those known as "portables" it is desirable that while the cabinet or box be well proportioned the machine as a whole be comparatively light in weight. To keep the cabinet as small as possible and yet of pleasing proportions it is necessary that it should be of small height.

Heretofore, when it was necessary to wind the motor of a portable where the cabinet was of small height and the winding crank extended horizontally from one side of the cabinet, it was necessary to move the machine to the edge of the table or other support on which it was resting since otherwise the hand gripping the winding handle would knock against the table or other support.

According to the present invention the winding gear of the motor is disposed above the motor frame whereby the winding crank is disposed higher than usual.

Also in one form or arrangement of the invention the winding gear of the motor is disposed above the motor board or cabinet partition with the winding crank also above the motor board and the parts are so arranged and constructed that the winding crank may be readily moved to winding position or to a stored position within the cabinet without disconnecting the winding crank and storing it as a loose part.

A further object is to provide a portable phonograph including a novel winding mechanism in combination with a horn, the winding mechanism being so arranged that a horn of exceptional length may be used without crimping, cutting or perforating it to provide space for the winding crank.

Other objects and advantages will become apparent from the following detailed description taken in connection with the accompanying drawing wherein the invention is shown in two forms. It is to be understood that this description and the accompanying drawing are for the purpose of disclosing satisfactory embodiments of the invention

and that the invention is not limited to the construction, combination and arrangement of parts shown as changes may be made and will readily suggest themselves to those skilled in the art. Therefore, reference must be had to the claims for a definition of the limitations of the invention.

In the drawing:

Figure 1 is top plan view of a portable phonograph, the top being omitted and the turntable being shown in dotted lines and showing the application of the invention.

Fig. 2 is a sectional view on the line 2—2 of Fig. 1; and

Fig. 3 is a similar view showing a slightly different arrangement.

Referring in detail to the drawing at 5 is shown the casing or main portion of a portable phonograph cabinet the top being omitted. Casing 5 includes front and rear walls 6 and 7 and side walls 8 and 9. Within the casing and below the upper edges of the walls thereof is a partition or motor board 10.

A motor 11 is supported by the motor board and includes a frame 12 mounting a spring barrel 13 to which is secured a relatively large gear 14 which through an intermediate gear 15 drives a small gear or pinion 16 secured to the usual upright turntable spindle or shaft 17 at its upper end carrying 80 and serving to rotate the turntable 18.

Referring more particularly to Figs. 1 and 2 the winding mechanism for the motor 11 is shown as disposed above the motor board 10. To this end the motor board is cut away 85 as at 19 and bearings 21, 22, and 23 on the upper side of the motor frame 12 project through the opening in the motor board and are disposed above the motor board. Also the spring barrel is mounted upon a shaft 90 24 likewise projecting above the motor frame 12 and the motor board 10 and at its upper end carrying a worm gear 25.

The winding crank 26 includes a handle 27 as is usual and includes a portion 28 and may include a threadable connection as at 29 or it may be integral in the form of the invention shown in Figs. 1 and 2. This portion 28 is rotatably mounted in the bearings 21, 22, and 23 and between the bearings 21 100 and

and 22 passes through a worm 30 meshing with the worm gear 25. Also between the bearings 21 and 22 and associated with the worm 30 is a back winding preventor 31 which as shown is in the form of a coil spring.

It will be obvious that by turning the crank 26 the spring in spring barrel 13 will be wound up since the shaft 24 will be rotated through the meshing of worm 30 and worm gear 25.

According to the invention as shown in Figs. 1 and 2 it is not necessary to disconnect the winding crank 26 in order to dispose the same within the casing 5 when the machine is not in use. To this end the portion 28 of the winding crank is slideable through the worm 30 and connected in driving relation with the worm through a sleeve 32 slotted as at 33 and with which the portion 28 has driving relation through the medium of a pin 34 carried by the portion 28 and disposed in the slot 33. Also, the side 9 of the casing is notched as at 35 and the winding crank 26 operates in this notch.

When it is desired to close the machine as for transportation, storage or the like it is but necessary to turn the crank 26 until its handle portion is disposed in a plane above and in line with the remainder of the crank and then push inwardly on the crank the latter passing through the notch or cut out portion 35, the pin 34 moving forwardly out of the slot 33 and the entire crank being disposed within the casing after which it may be turned down to lie against the motor board 10 in the position in dotted lines in Fig. 1. Of course, to again extend the crank to operative position it is but necessary to turn it to dispose the handle 27 above and in line with the major portion of the crank and to then pull outwardly on the same to have the crank extend through the notch 35 as shown in Figs. 1 and 2.

Through the use of a motor and winding mechanism as described additional space within the casing 5 is made available for occupancy by an enlarged horn or amplifier of channel formation having its open side 50 closed by the partition or motor board. This is illustrated and as shown the amplifier 36 extends from the base of a tone arm 37 shown in dotted lines in Fig. 1 and carrying a reproducer 38 also shown in dotted lines.

The base of the tone arm 37 is at one rear corner of the motor board 10 and the amplifier 36 extends along the side wall 9 of the casing, along the front wall 6 of the casing and is curved back along the side wall 8 of the casing discharging through an opening 39 in the motor board 10 at the back of the casing.

Since the winding crank is disposed above the motor board 10 it does not in any way interfere with the horn 36 and it is not nec-

essary to crimp or perforate the horn to make space for the winding crank. Further, owing to the fact that the winding mechanism is disposed above the motor board, a cabinet of less depth may be used and space 70 will be provided in order that the winding crank may be operated without the occasion for moving the casing 5 to the edge of the table or other support since the winding crank will be considerably elevated above its 75 usual position.

In Fig. 3 is shown a slight modification. In this figure the entire motor 11 including the bearings 21, 22 and 23 and the winding gears 25 and 30 are shown disposed below 80 the motor board 10. With this form of the invention the winding crank 26 extends through a perforation 40 in the side wall 9 of the casing or cabinet 5 and must be threaded as at 29 in order that it may be detached 85 from the portion 28 keyed or otherwise secured to the worm 30.

In this last form of the invention the winding crank 26 would have to be unscrewed at 29 in order that it may be removed and disposed within the casing when the machine is closed as for storage, transportation or the like.

Having thus described the invention what is claimed is:

1. In a talking machine, a casing, a partition within the casing, a spring motor, disposed below said partition, a winding means including a crank and a gear disposed above said partition for winding the spring of said 100 motor, and a sliding connection between the crank and gear whereby the crank may be slid into a position within the casing.

2. In a talking machine, a casing, a partition within the said casing, a turntable above 105 said partition, a spring motor below said partition and in driving relation with said turntable, and a winding means for said motor disposed above said partition and beneath said turntable, said winding means including 110 a gear and a crank and a sliding connection between the gear and crank whereby the crank may be slid into a position within the casing and partially concealed by the turntable.

3. In a talking machine, a casing, a partition within said casing and disposed below the upper edge thereof, a spring motor within said casing and below said partition, winding means for the spring of said motor, said 120 winding means including gearing disposed above said partition, a crank for operating said winding gearing, and one wall of said casing being notched at its upper edge whereby the crank may be moved to dispose its handle portion at the side of the casing and in operative position and may be moved to dispose its handle within the casing in inoperative position without disconnecting the winding crank.

4. The combination as in claim 3 including a turntable disposed above said partition and said winding mechanism including a portion of the crank being disposed beneath said turntable.

5. In a talking machine, a casing, a partition within the casing, a spring motor disposed below said partition, and a winding means including a crank horizontally disposed above said partition for winding the spring of said motor, a means to be rotated by the crank, and a sliding connection between the crank and said means whereby the crank may be slid through said means to a position above the partition and within the casing.

6. The combination as in claim 3 said crank being connected with said gearing by a pin and slot connection.

7. In a talking machine, a casing, a turntable, a spring motor in driving relation with the turntable, a winding means for the motor, said winding means including a gear and a crank and means mounting the crank for sliding movement through the gear whereby the crank may be slid to an operative position and after use to an inoperative position.

8. In a spring motor comprising a frame including a top plate, a winding shaft for the spring of said motor extending above said top plate and having a gear mounted thereon, a bearing on said top plate and extending above the same, a winding means including a gear in mesh with the gear on the winding shaft, said winding gear mounted in said bearing, and said winding means including a shaft having a sliding connection with the winding gear.

Signed at Bridgeport, in the county of
Fairfield and State of Connecticut, this 11
day of April, A. D. 1930.

GUSTAVE F. BAHR.
